UNITED STATES PATENT OFFICE.

DAVID D. WALKER, OF GRAND VIEW, IDAHO.

STRAINER.

1,427,565.

Specification of Letters Patent. Patented Aug. 29, 1922.

Application filed August 5, 1920. Serial No. 401,435.

To all whom it may concern:

Be it known that I, DAVID D. WALKER, a citizen of the United States, residing at Grand View, in the county of Owyhee and State of Idaho, have invented certain new and useful Improvements in Strainers, of which the following is a specification.

This invention relates to strainers especially adapted for straining milk.

10 An object of the invention is to provide a strainer which will insure the passage of the milk through a plurality of straining mediums before ultimately passing into the receptacle from which, or in which the milk 15 will be vended.

Another object of the invention is to provide a strainer which may be quickly and conveniently dismantled to permit thorough cleaning of every part of the strainer.

20 The above and other objects of this invention will be in part described and in part understood from the following description of the present preferred form of the invention taken in connection with the accompanying drawings, wherein:

Fig. 1, is a vertical sectional view of a strainer constructed in accordance with my invention showing the clamping ring separated therefrom, and

30 Fig. 2, is a sectional view taken on the line 2—2 of Fig. 1, and looking in the direction of the arrow.

In the drawings, a strainer body 3 is provided which in this instance is shown to 35 be of substantially hemispherical shape, although any other desired shape of body may be used. The body is provided with an opening 4 in the bottom thereof, the latter being pressed up to provide an up- 40 standing base 5, the said base constituting the wall of the opening 4.

A straining element 6 which in the present instance consists of a circular wire mesh body is mounted upon the base 5 across the 45 opening 4. The straining element is clamped on the base by a cap 7, the latter constituting a cylinder, the upper end 8 of which is closed, and the lower end thereof re- 50 versely folded as indicated at 9 and then turned outwardly at right angles providing an annulus 10. The annulus serves as a wall for an opening 11 formed in the bottom of said cap. Arcuate openings are formed at intervals in the cap 7 adjacent the closed 55 upper end 8 thereof, each opening having a wire mesh panel 12 detachably mounted

thereover. As shown to advantage in Fig. 1 of the drawings, these arcuate openings fall short of the annulus 10.

A spout 13 issues from the bottom face 60 of the body 3, consisting of an annular collar, the upper marginal edge of which is bent inwardly at right angles and is secured to said body in any suitable manner. When in this position the inner margin 65 of the spout will be in a plane coincident with the plane of the inner wall on the pressed up portion of said body 3. The lower marginal edge of said collar is turned upwardly into engagement with the outer 70 periphery of the latter to reinforce the same. A suitable straining cloth or the like as indicated by the dotted lines 14 is adapted to be placed over the outlet end of the spout and is held in position by a clamping collar 75 15. The latter slides over the outer periphery of said collar so as to clamp the cloth 14 between said collar and rim in a manner indicated by dotted lines in Fig. 1. By folding over the lower margin of said 80 spout or collar 13 to reinforce the same, an enlargement is provided which will yieldingly engage the clamping ring 15 to retain the latter from accidental displacement.

In use, the straining element 6 is mounted 85 upon the base 5, following which the cap 7 is slid downwardly onto the base so as to assume the position shown in Fig. 1 of the drawings. Since the upper end of the cap is closed, the milk poured into the body 90 3 must pass through the strainers 12 thence through the strainer 6 and ultimately through the straining cloth 14 into a receptacle placed therebeneath.

What is claimed is:

1. A milk strainer including a body provided with an opening, a screening element arranged over the opening, a cap detachably holding said element over said opening, said cap having a closed upper end and 100 openings in its side, a spout depending from said body, and a clamping ring for securing a screening element over the spout.

2. A milk strainer including a body the bottom of which is pressed upwardly to provide an upstanding base, a screening element arranged on the base, a cap snugly engaging said base and clamping said screening element thereon, said cap having an imperforate top and screened openings in 110 its side.

3. A milk strainer including a body the

bottom of which is pressed upwardly to provide an upstanding base, a screening element arranged on the base, a cap snugly engaging said base and clamping said screening element thereon, said cap having an imperforate top and screened openings in its side, a spout depending from said body for the reception of a secondary screening ele-

ment, and a ring to clamp said secondary screening element on the spout.

In testimony whereof I affix my signature in presence of two witnesses.

DAVID D. WALKER.
